THE COLUMBIA PLANOGRAPH CO., WASHINGTON, D. C.

UNITED STATES PATENT OFFICE.

NEWELL V. DYER, OF HOLBROOK, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING-MACHINE.

1,308,776.

Specification of Letters Patent.

Patented July 8, 1919.

Application filed November 18, 1916. Serial No. 132,191.

To all whom it may concern:

Be it known that I, NEWELL V. DYER, a citizen of the United States, and resident of Holbrook, county of Norfolk, State of Massachusetts, have invented an Improvement in Skiving-Machines, of which the following is a specification, like characters on the drawing representing like parts.

This invention relates to skiving machines and is herein illustrated as embodied in a machine for skiving the edges of parts of uppers of boots and shoes.

Hitherto, except when the mechanism of my prior Patent No. 1,138,645 has been used, it has been necessary to adjust certain parts of leather skiving machines whenever a scarf of different width or angle was desired. With the patented mechanism it is possible to produce two scarfs of different width without adjusting any part of the machine. If, however, a scarf of different angle is desired, adjustment is necessary. In the manufacture of certain high grade shoes it is desirable to produce three or four different scarfs upon the same piece of leather; and to accomplish this certain adjustments have been necessary or else the pieces of leather had to be subjected to skiving operations on two or more machines.

One feature of the present invention comprises a machine having two skiving mechanisms located in proximity to each other and improved means for making the initial adjustments. In the illustrative machine the skiving mechanisms are located at different levels so as to permit ready presentation of the work first to one and then to the other, and the mechanism for adjusting the knife shafts are located on opposite sides of said shafts. With this construction two scarfs of different angles or bevels may be produced without any change of adjustment.

Another feature of the machine comprises a construction in which the feed mechanism is supported on a movable member so that the whole feed mechanism may be moved to one side to permit ready access to the knife and the knife grinding mechanism. This construction greatly facilitates accurate grinding of the knife as well as the removal of a worn knife and its replacement by a new one.

A further feature of the invention com-

prises improved means for driving the knife and feed mechanism by means of belts. 55

These and other features of the invention, including certain details of construction and combinations of parts, will be described as embodied in an illustrative machine and defined in the appended claims. 60

In the drawings:

Figure 1 is a front elevation of a skiving machine in which the invention is embodied;

Fig. 2 is a plan of the machine; 65

Fig. 3 is a side partial elevation thereof as viewed from the left of Fig. 1;

Fig. 4 is a detail plan with parts broken away and showing the supplemental frame or arm released and swung with its parts 70 outward from the main frame;

Fig. 5 is a vertical section on line 5—5 of Fig. 3;

Fig. 6 is an enlarged detail with portions broken away of parts relating to the feed 75 rolls, the skiving knife and associated parts illustrating more particularly the mechanism for adjusting one of the knives;

Fig. 7 is an enlarged horizontal detail on line 7—7 on Fig. 1; 80

Fig. 8 is an enlarged elevation of the skiving knife grinding mechanism with portions broken away to illustrate the details thereof, and

Fig. 9 is a detail elevation of the driving 85 shaft frame with portions shown broken away to illustrate the adjustment features.

In the drawings 20 represents a suitable frame provided with a base 21 adapted to be secured in any convenient or desired manner to a table, bench, or other foundation. This frame is also provided at the top thereof with a horizontally projecting arm 22 which is bifurcated at 23 to form the supporting portions 24 and 25 adapted to co-operate with a supplemental frame 27. The supplemental frame is pivoted to the under side of the supporting portion 24 by means of the pivot bolt 28 provided with the enlarged head 29 resting in a proper counterbore in said supporting portion, and beneath said supplemental frame I provide on said bolt a nut 30 or the like to engage the under face of said frame. The opposite end of said supplemental 105 frame may therefore be swung about the

pivot 28 toward or from the supporting portion 25. The free end of the supplemental frame is provided with a slot 31, adapted to coöperate with the clamp bolt 32 secured to the supporting portion 25, and having a wing clamp-nut 33 to engage the under face of said frame about the slot in order that the supplementary frame may be securely clamped to the under face of said portion 25.

10 The supplemental frame 27 is adapted to support the feeding and gaging mechanisms together with the driving means for the feeding mechanism as will now be described.

15 This supplemental frame is provided with bearings 37-37 and 38-38, and rotatable therein are the shafts 39 and 40 respectively. The shaft 39 has secured thereto in any suitable manner a gear 42 which meshes with

20 an idler gear 43 on a stud shaft 44 projecting from the aforesaid supplemental frame. The shaft 40 is likewise equipped with a gear 45 which meshes with the idler gear 43 so that when the shaft 39 is rotated by

25 the pulley 47 secured thereto, the shaft 40 will also rotate and in the same direction as the shaft 39. To the shafts 39 and 40 are secured the feed rolls 48 and 49 respectively with work supporting faces 50 and feed

30 faces 51. The faces 50 are frusto-conical while the feed faces 51 are cylindrical and offset from the faces 50 by diverging or angular shoulders 52.

Coöperating with the feed rolls 48 and 49 and engaging the feed faces 51 thereof are relatively thin rotatable feed disks 55 and 56 respectively having their shafts 58 and 59 parallel one with the other and both perpendicular to the shafts 39 and 40. For 40 the shaft 58 are provided bearings 61 and 62 in the supplemental frame 27 with a tie piece or pillar 63 connecting said bearings; and bearings 65 and 66 for the shaft 59 are also formed in the supplemental frame 27.

45 Each shaft 58 and 59 is surrounded by a spring 68 having one end thereof engaging a collar 69 secured to said shaft in any suitable manner, as by a set screw or the like, the other end bearing against the under

50 surface of the bearing 62 or 66, each spring normally forcing its collar 69 downward. The set screws permit adjustment of the collars along the shafts to increase or decrease the tension of said springs. Pulleys

55 71 and 72 are splined to the shafts 58 and 59 respectively above the bearings 62 and 66. A crossed belt 73 engages the pulley 71, is then passed over a pair of idler pulleys 75 after which it is wrapped about the driv-

60 ing pulley 76 secured in any desired manner to the shaft 39. A bracket 78 secured to or integral with the supplemental frame 27 is provided with a stud shaft 80 on which the idler pulleys 75 are rotatable. A similar stud shaft 82 is also located on the

bracket 78, and rotatable thereon are another pair of idler pulleys 83. A belt 84 passes about the pulley 72 thence over said idler pulleys 83 after which it is crossed and wrapped around the driving pulley 85 70 fastened on the shaft 39.

All the feed mechanism, which has been described above, is mounted upon the supplemental frame 27 and may be swung out at any time about the pivot 28, as illustrated in Fig. 4 to permit access to the skiving mechanism and grinding mechanism which are carried by the main frame of the machine.

To the rear of the feed rolls 48 and 49 are skiving knives 90 and 91 respectively carried by inclined shafts 92 and 93 to the upper ends of which are keyed pulleys 95 and 96. These shafts are inclined in substantially

the same manner and may be adjusted in 85 different directions as will now be described. Referring to Fig. 6, it will be seen that the knife shaft 92 is rotatable in bearings 97 on an adjustable head 98. This head is pro-

vided with inclined ways 100 adapted to engage with and slide on the co-acting ways 101 on the swiveled head 102. A feed screw 103 is held against longitudinal movement at one end of the said swiveled head and co- 95 operates with the screw threaded lug 104 on the adjustable head 98 to enable the latter to be moved up and down on the swiveled head. The swiveled head 102 is pivoted at 106 be-

tween the ears or guiding portions 107 on a translating head 108 having horizontal ways 109 to engage co-acting ways 110 on a cross head 111, the shape of the ways being such as to form a dovetail connection. The ways 109 and 110 extend laterally in order that

100 the translating head 108 may be movable in a path substantially parallel to the axis of the feed roll 48 so that the knife 90 may be moved along the face 50 of said roll. The translating head 108 is provided at the bottom thereof with a translating rack 115 105 adapted to mesh with and be moved by a translating gear 116 rotatable in suitable bearings in the cross head 111 and provided with a shaft 117 having a knurled head 118.

The cross head 111 is also provided with 115 ways 120 at the bottom thereof transverse to the ways 110, to coöperate with the ways 121 on a base 122 secured to the stationary supporting portion 24 of the frame. A feed screw 125 having a knurled head is held against longitudinal movement by the bearing 126 secured to the base 122 and is adapted to coöperate with a screw-threaded bore 127 through the cross head 111 to enable the latter to be moved with respect to the former carrying with it the other associated parts hereinbefore described to adjust the knife 90 forward and backward. With the construction thus far described manipulation

120 of the screw 103 raises or lowers the 130

125

knife and manipulation of the pinion 116 and of the screw 125 effects respectively an adjustment of the knife longitudinally of the feed roll and an adjustment toward and 5 from the operator. In order to vary the angular inclination of the knife about the pivot 106, the head 102 has a slot 130 the walls of which are engaged by a stud or pin 131, said stud being eccentrically mounted in 10 one face of a disk 132 rotatably mounted in a bore in one of the ears 107. A shaft 134 and knurled head 135 furnish means for turning the disk to effect angular adjustment of the head 102 and consequently of 15 the knife. When the disk 132 is rotated, the stud will throw the free end of the swiveled head upward about the pivot 106 thereby changing the angular relation of the swiveled head 102 with respect to the translating 20 head 108 and also changing the angular relation of the knife 90 with respect to the face 50 of its bed roll. By this means the width or angle of a scarf may be changed. In order to lock the swiveled head 25 102 to the translating head 108 in any adjusted relation, a locking screw 138 is tapped through one ear 107 of the translating head 108 and bears against one face of the swiveled head as will be seen in Fig. 7.

30 The shaft 93 of the knife 91 is rotatably supported in bearings 140 forming a part of the adjustable head 141 vertically slideable at 142 on the swiveled head 143. The swiveled head 143 is provided with an adjusting screw 144 held against longitudinal movement with respect thereto and coöperating with a lug on the adjustable head 141 in the same manner as described for the adjustable head 98 and swiveled head 102. 35

40 The swiveled or pivoted head 143 is pivoted at 146 to the translating head 147, and the mounting of the pivoted head is in general similar to that of the pivoted head 102 of the knife 90 except that, whereas in the 45 head 102 the slot 130 is located between the pivot 106 and the knife shaft 92, the relative positions of the pivot 146 and the slot 149 are reversed in the head 143, the pivot 146 being located between the slot 149 and the 50 knife shaft 93. An eccentric adjusting stud 148, similar to the eccentric adjusting stud 131 is positioned to operate in the slot 149 to effect angular adjustment of the knife. Although the mechanisms for adjusting the 55 knives are similar, it should be noted that their locations relatively to their respective knife shafts are different in that they are located on opposite sides of the knife shafts. The translating head 147 is slideable at 60 on the cross head 152 and the former is provided with a translating rack 153 coöperating with the translating gear 154 fixed to a shaft 155 rotatable in bearings in the latter head and provided with a knurled adjusting 65 head 156. The cross head 152 is slideable at 158 on the base 159 secured to the supporting portion 25 of the frame of the machine as described for the base 122. Relative adjustment is obtained between the cross head 152 and the base 159 by means of a feed 70 screw 161 tapped through the former and held against longitudinal movement in the latter. The knife 91 may thus be adjusted similarly to the knife 90.

As the knives 90 and 91 become dull 75 through use they must be frequently sharpened while revolving at high speed. To accomplish this without changing the angle of the cutting edge thereof and irrespective of their relative angularity to their 80 respective bed rolls the following grinding means are provided. Swiveled on the pivot 106 is a grinder frame 165 provided with a segmental slot 166 through which is extended a clamp screw 167 having a suitable 85 shoulder to engage the outer face of said frame 165, said screw being threaded into one guiding portion 107 forming the rear part of the translating head 108. Therefore, whatever lateral movement is imparted 90 to the knife 90 is also imparted to the grinder frame 165 which supports the grinding or sharpening tool. The grinder frame 165 is provided with bearings 168 and 169 the former adapted to receive therein the 95 grinder shaft 171 and the latter forming a guide for the shaft sleeve 172 which forms the upper bearing surface for the said shaft. At the top of the shaft is a swiveled shoulder cap 173, and interposed between said cap 100 and the sleeve 172 is a spring 175 normally tending to throw the shaft upward until a clutch collar 177, which is fast to the shaft, engages the lower end of said sleeve thereby limiting the upward movement of said 105 shaft. The clutch collar is provided with a set screw 178 engaging the shaft to provide means whereby the position of the collar may be changed to increase or decrease the tension of the spring 175. This collar serves 110 also to limit the extent of upward movement of said shaft and to drive or rotate the latter when the lugs 180 on said collar are brought into engagement with the notches or holes 181 in the face of the idler driving pulley 182 115 which is freely revoluble on the shaft. This driving pulley 182 is loosely mounted on the shaft 171 so that it may rotate or move up and down thereon and is held substantially in the position shown only by the tension of 120 the belt 229 presently to be described. This construction obviates the necessity which might otherwise exist of providing certain guide pulleys for the belt, and at the same time maintains the pulley in position with 125 sufficient firmness to cause it to rotate the grinder when the lugs 180 are moved into engagement with the holes 181. The purpose of the sleeve 172 is to permit adjustment of the shaft 171 so as to regulate the 130

distance through which the shaft must be pushed downwardly by pressing upon the cap 173 before the grinder 186 contacts with the knife. To this end the sleeve is provided 5 with a rack 188 with which meshes a pinion 189, the pinion being fast on a shaft 190 one end of which carries a knurled head by which it may be turned. After the shaft has been adjusted into the position desired 10 by the operator, the grinding of the knife is accomplished by pushing down on the cap 173. Or, if desired, the whole downward movement of the grinder shaft may be effected by turning the pinion 189. Since the 15 grinder frame 165 is movable on the pivot 106 with the knife 90, any transverse or lateral movement imparted to the latter is also imparted to the former, and the grinder 186 is always in a proper relation above the 20 knife. In addition the slot 166 and clamp screw 167 permit setting or clamping the grinder mechanism in any desired angular relation to the knife 90 so as always to produce a relatively thin sharpened edge there- 25 on. The result is that the knife is at all times properly sharpened producing a clean cut along the line of the scarf. It will be noted that, as the entire sharpening or grinding mechanism is to the rear of and 30 above the knife and the means for adjusting the grinder 186 are at the top of the mechanism, there is no necessity for the operator's hands to approach too closely to the rapidly revolving knife 90, thus obviating 35 the danger of accidental contact of the operator's fingers with the knife.

The knife 91 is provided with grinder mechanism similar in construction to that described for the knife 90 except that, in- 40 stead of the shaft for the grinder 194 being inclined toward its fulcrum or pivot point 146 on the translating head 147, the direction of inclination is away from the latter and substantially parallel with the shaft 45 171 of the grinder 186 or parallel with the shaft 93 of the said knife 91. Another difference in construction consists in having the adjusting screw 195 corresponding to 167 located beyond and to the left of the 50 pivot 146 and not interposed between the pivot and driving shaft as illustrated in Fig. 8.

When it is desired to grind the knife or knives the clamp nut 33 is unscrewed or 55 released allowing the end of the supplemental frame 27, which is provided with the slot 31, to be detached from the supporting portion 25, after which the supplemental frame is swung about the pivot bolt 28 away 60 from the front of the machine, as indicated in Fig. 4, thereby moving the feed mechanisms out of coöperative relation to the knives 90 and 91 and their grinding mechanisms and permitting access to the knives. 65 This feature is highly important in that

complete access is had to all of the knife and grinder parts both for sharpening and repairing or renewal. There is also less danger of the clothing or the hands of the operator being drawn through the feed 70 mechanism to the knife during the close inspection which is necessary during the grinding operation. Then too, for the purpose of renewal or replacement of the said knives, no other parts of the machine need 75 be disassembled or thrown out of adjustment as the knives are clearly exposed with no intervening structure to interfere with their manipulation.

The means for rotating all the driving pul- 80 leys described heretofore consists of the shaft 212 rotatable in the bearings 213 at opposite sides of an adjustable and floating yoke-like frame 214 located to the rear of the frame 27, see Figs. 3, 5 and 9. Keyed 85 to said shaft 212 in any suitable manner is a main driving pulley 215. A driving pulley 218 on the shaft 212 is connected to the pulley 47 by means of the belt 219. Driving pulleys 222 and 223 on said shaft are connected by belts 224 and 225 to the pulleys 95 and 96 respectively. Also on said shaft are pulleys 227 and 228 connected by belts 229 and 230 to the pulleys 182 on the grinder shafts 171 to drive the grinders 186 and 194. 90 The yoke frame 214 is provided at the bottom with a pair of forked portions 232 spanning the frame 20 to engage with a pin 233 or the like. The upper portion 235 of the yoke frame is channel-shaped to pass 100 over both sides of the frame 20 to provide a means of support and a convenient coöperating part for an adjustment feature. At the top of the frame 214 is provided an ad- 105 justing screw 237 tapped therethrough and having the end resting in a recess in a sliding saddle block 238. A lateral adjusting screw 239 is tapped through a lug 240 fast to the main frame and bears against an up- 110 right 241 at the forward end of the saddle block. A spring 243 interposed between the stationary lug 244 and the upright 245 on the sliding block tends at all times in con- 115 junction with the pull of the belts to swing the saddle block and upper end of the yoke frame 214 forward against the screw 239, the spring 243 providing at the same time a convenient yielding means against the force of which the saddle block may be ad- 120 justed to take up any slack or looseness in the belts.

Gages or guiding means are necessary in order that the work may be properly guided on the bed roll in correct relation to the knives 90 and 91 for a determined width of 125 scarf. Therefore to the front face of the supplemental frame 27 there is secured ad- 130 jacent to each feed roll a depending gage 250 having a slot 251 adapted to coöperate with a bolt 252 on the supplemental frame in

order that the gage may be adjusted longitudinally of the rolls 48 and 49. Horizontal ears 255 and 256 project from each gage at different heights; and each ear is provided 5 with a bore, bearing, or the like to receive a vertically slideable rod 258 at the bottom of which is a presser-foot 259 adapted to rest upon the leather just forward of the cutting edges of the knives. Each presser- 10 foot has a guiding stem 260 slideable in the end of the ear 256 so that the presser-foot can not rotate or move except vertically. At the top of each rod 258 is a nut 261 screwed thereon and arranged to rest on the top of 15 the ear 255 in order to limit the downward movement of the rod 258 and presser foot 259. By means of the adjusting nuts 261, the presser feet may be brought into very close relation to the feed rolls 48 and 49 or 20 may be more or less removed therefrom to accommodate different thicknesses of leather. In order to maintain a pressure of the presser foot against the leather there is provided above each ear 256 a nut 263, and interposed between the latter and the ears 255 25 are coiled springs 264 encircling the rods 258. These springs, bearing against the ears 255 and the nuts 263 cause sufficient downward pressure to control properly the leather 30 and to guide the same to the rapidly revolving knives 90 and 91.

In Fig. 6 there is shown attached to the bearing 97 a portion of a guard structure for the knife comprising a U-shaped member having depending legs 269 and 270, the leg 270 being in two parts hinged together at 271, the upper stationary part of the leg 270 having a stop 272 against which the lower hinged part is normally held by gravity. By lifting up the lower hinged part of the leg 270 an oil stone or other bur-removing member may be applied to the under side of the edge of the knife at a point adjacent to the lower end of the hinged portion. 45

In the use of the machine, the various adjustments of the feed, gage and knife mechanisms having been made, the operator first skives one edge of a piece of leather or other material on one of the skiving mechanisms, and then another edge on the other skiving mechanism. It should be noted that these mechanisms are spaced apart in the general direction in which the feed roll shafts extend and are located at different levels. 50 This construction and arrangement permits a piece of work to be fed without interference to either mechanism and to be swung freely when a curved edge is encountered. 55

This application is a continuation, so far as common subject-matter is concerned, of my prior application Serial No. 58,571, filed October 29, 1915.

Although the invention has been set forth 65 as embodied in a particular machine, it

should be understood that the invention is not limited in the scope of its application to the particular machine which has been shown and described.

Having thus described my invention, 70 what I claim as new and desire to secure by Letters Patent is:

1. In a skiving machine, a main frame, a plurality of independently operated skiving knives upon said frame, a supplementary frame pivoted on said main frame, and a plurality of feed mechanisms upon said supplementary frame adapted respectively to coöperate with said knife mechanisms. 75

2. In a skiving machine, a main frame, a 80 plurality of skiving knives thereon, a supplementary frame having one end thereof pivoted to said main frame and the other end detachably clamped thereto, and feed roll mechanisms rotatable in said supplementary frame and coöperating with said knives. 85

3. In a skiving machine, a main frame, a plurality of skiving knives thereon, a supplementary frame having one end pivoted to a portion of said main frame and the opposite end detachably clamped to another portion of the main frame, and a plurality of feed roll mechanisms rotatable in said supplementary frame and arranged to coöperate with one of said knife mechanisms. 90

4. In a skiving machine, a main frame, a plurality of skiving knife mechanisms thereon, a supplementary frame having one end pivoted to a portion of the main frame and the other end detachably secured to another portion of said frame, a plurality of feed roll mechanisms revoluble in said supplementary frame each coöperating with a skiving knife mechanism, a feed disk for each feed roll, and driving means on said main frame coöperating with driving means on said feed rolls for rotating said feed rolls 100 and feed disks. 105

5. In a skiving machine, a main frame, a plurality of rotatable skiving knives thereon, a supplementary frame having one end pivoted to a portion of said main frame and the opposite end detachably secured to another portion of said main frame, a plurality of feed rolls rotatable in said supplementary frame on horizontal axes each coöperating with a skiving knife, and a feed disk coöperating with each feed roll, said feed disks being mounted on vertical axes. 115

6. In a skiving machine, a main frame, a plurality of rotatable skiving knives thereon a supplementary frame having one end pivoted to a portion of said main frame and the opposite end detachably secured to another portion of said main frame, a plurality of horizontally disposed feed rolls rotatable in said supplementary frame each coöperating with a skiving knife, a feed disk mounted on a vertical axis coöperating 120 125

130

- with each of said feed rolls, and driving means on said main frame coöperating with driving means on the supplementary frame to rotate said feed rolls and said feed disks.
- 5 7. In a skiving machine, a main frame, a plurality of skiving knife mechanisms thereon, a supplementary frame having one end thereof pivoted to a portion of the main frame and the other end thereof 10 detachably secured to another portion of said frame, a plurality of spring pressed feed members revoluble in said supplementary frame each coöperating with a skiving knife mechanism, and driving means on 15 said main frame coöperating with driving means on said feed members for rotating the same.
8. In a skiving machine, a main frame, a plurality of adjustably mounted and 20 rotatable skiving knives located between different portions of said frame, a plurality of feed rolls, and a support for the rolls pivoted adjacent to one knife and provided with means adapted to be detachably secured 25 to said frame adjacent to another knife each feed roll being adapted to coöperate with a skiving knife.
9. In a skiving machine, a main frame, a plurality of adjustable and rotatable skiving knives thereon, feed rolls for the knives, a support for the rolls pivoted adjacent to one knife, shafts for the feed rolls, means for driving one shaft from the other, a feed disk for each feed roll, and means connecting 30 one of said feed roll shafts to said feed disks to rotate the latter.
10. In a skiving machine, a main frame, a plurality of adjustably mounted and rotatable skiving knives thereon, a supplementary frame having one end thereof pivoted to one portion of said main frame and the opposite end thereof detachably secured to another portion of said main frame, a plurality 40 of horizontal shafts rotatable in said supplementary frame, a feed roll on each shaft coöperating with a skiving knife, a feed disk for each feed roll, vertical shafts by which the feed disks are carried, and driving means interposed between one of 45 said horizontal shafts and all of said vertical shafts for rotating the latter.
11. In a skiving machine, a plurality of knife mechanisms, a swiveled frame and feed mechanisms and gage mechanisms 50 mounted thereon, said swiveled frame being adapted to move the feed and gage mechanisms into and out of coöperative relation with said knife mechanisms.
12. In a skiving machine, a main frame, a plurality of knife mechanisms thereon, an adjustable grinder mechanism for each knife 55 mechanism, a swiveled frame on said main frame, and rotatable feed mechanisms supported by said swiveled frame, said latter frame being adapted to be moved to bring

the feed mechanisms into and out of coöperative relation with the knife mechanisms.

13. In a skiving machine, a main frame, a plurality of skiving knife mechanisms swiveled thereon, a grinder mechanism coöperating with each knife mechanism, a frame swiveled on said main frame, and rotatable feed mechanisms mounted on said swiveled frame each coöperating with a knife mechanism. 70

14. In a skiving machine, a main frame, a plurality of knife mechanisms thereon, an adjustable grinder mechanism for each knife mechanism, a frame swiveled on said main frame, rotatable feed mechanisms supported by said swiveled frame, said latter frame being adapted to be moved to carry the feed mechanisms into and out of coöperative relation with the knife mechanisms, and means for rotating said grinder, said knife and 80 said feed mechanisms.

15. In a skiving machine, a main frame, a plurality of skiving knife mechanisms swiveled thereon, a grinder mechanism coöperating with each knife mechanism, a frame swiveled on said main frame, rotatable feed mechanisms supported by said swiveled frame each mechanism coöperating with a knife mechanism, and means for rotating said grinder, said knife and 90 said feed mechanisms. 95

16. In a skiving machine, a main frame, a plurality of skiving knife mechanisms swiveled thereon, a grinder mechanism coöperating with each knife mechanism, a frame swiveled on said main frame, rotatable feed mechanisms supported by said swiveled frame each mechanism coöperating with a knife mechanism, an adjustable frame and driving means for said grinder, said 100 knife and said feeding mechanisms mounted on said adjustable frame.

17. In a skiving machine, a main frame, a plurality of knife mechanisms thereon, an adjustable grinder mechanism for each knife 110 mechanism, a frame swiveled on said main frame, rotatable feed mechanisms supported by said swiveled frame said latter frame being adapted to be moved to carry the feed mechanisms into and out of coöperative relation with the knife mechanisms, an adjustable frame and driving means thereon for said grinder, said knife and said feeding mechanisms. 115

18. In a skiving machine, a main frame, a supplemental frame pivoted thereon, a floating frame mounted upon said main frame, a skiving knife upon said main frame, feed roll mechanism upon said supplemental frame, and driving mechanism 125 upon said floating frame coöperating with said knife mechanism and said feed mechanism.

19. In a skiving machine, a main frame, a supplemental frame pivoted thereon, a 130

- floating frame mounted upon said main frame, a plurality of skiving knives upon said main frame, a plurality of feed roll mechanisms upon said supplemental frame, 5 and driving mechanism upon said floating frame coöperating with said knife mechanisms and said feed mechanisms.
20. In a skiving machine, a main frame, a supplemental frame pivoted thereon, a floating frame mounted upon said main frame, an adjustable skiving knife upon said main frame, an adjustable feed roll mechanism upon said supplemental frame, and driving mechanism upon said floating frame 10 coöperating with said knife mechanism and said feed mechanism.
21. In a skiving machine, a main frame, a frame swiveled thereon, a floating frame mounted upon said main frame, a plurality 15 of adjustable skiving knives upon said main frame, a plurality of feed roll mechanisms upon said swiveled frame, and driving mechanism upon said floating frame coöperating with said adjustable knives and said feed 25 mechanisms.
22. In a skiving machine, a main frame, a skiving knife mechanism pivoted thereon, a feed roll mechanism pivoted on said main frame, pulleys on said knife mechanism and 30 said feed mechanism, a driving pulley frame pivoted to said main frame, driving pulleys mounted thereon, and belts coöperating with the driving pulleys, the skiving knife pulley and the feed pulley.
- 35 23. In a skiving machine, a main frame, a skiving knife mechanism thereon, feed roll mechanism for said knife mechanism, a frame adjustably mounted on said main frame, and driving mechanism on said adjustable 40 frame coöperating with said knife mechanism and said feed roll mechanism for rotating the knife and feed roll.
24. In a skiving machine, a main frame, skiving knife mechanism thereon, feed roll 45 mechanism for said knife mechanism, a frame having one end thereof swiveled to said main frame and the opposite end thereof of adjustable relative to said knife and feed mechanisms, and driving means on said last- 50 mentioned frame coöperating with said knife and feed mechanisms for rotating the knife and feed roll.
25. In a skiving machine, a main frame, skiving knife mechanism thereon, feed roll 55 mechanism for said knife mechanism, a yoke-like frame having one end thereof pivoted to said main frame, means on the opposite end thereof for coöperating with said main frame to adjust the yoke-like frame 60 relatively to said knife and feed mechanisms, and driving means on said latter frame coöperating with said knife and feed roll mechanism to rotate the knife and feed roll.
- 65 26. In a skiving machine, a main frame, a rotatable skiving knife, pivoted means supporting said skiving knife and interposed between the same and said frame, mechanism for adjusting the said pivoted means, and adjustable means between the 70 pivoted means and said knife for adjusting the knife relatively to the pivoted means.
27. In a skiving machine, a main frame, a skiving knife mechanism pivoted thereon, a grinder swiveled about the pivot of the 75 skiving knife, means for adjusting the grinder toward and from the said skiving knife, and resilient means for returning the grinder to its normal inoperative position.
28. In a skiving machine, a main frame, 80 skiving knife mechanism pivoted thereon, a grinder swiveled about the pivot of the skiving knife, means for adjusting the grinder toward and from the skiving knife, resilient means for returning the grinder to 85 the normal inoperative position, and clamping means interposed between said grinder and said skiving knife to secure the former in adjusted relation to the latter.
29. In a skiving machine, a main frame, a 90 rotatable skiving knife, pivoted means supporting said skiving knife and interposed between the same and said frame, mechanism for adjusting said pivoted means, a supplementary frame pivoted on said main 95 frame, feed roll mechanism rotatable in said supplementary frame, an adjustable yoke frame on said main frame, and driving means on said yoke frame coöperating with said skiving knife and feed roll mechanism 100 for rotating the knife and feed rolls.
30. A machine of the class described having, in combination, two spaced supports, two skiving knives, knife shafts located in the space between the supports and inclined 105 in substantially the same manner, bearings for the shafts carried by the supports, feed mechanisms coöperating respectively with the knives, and means located respectively on the same sides of the shafts as are the 110 supports for adjusting the knife shafts and knives similarly with respect to their respective feed mechanisms.
31. A machine of the class described having, in combination, a frame having two 115 supporting portions spaced apart vertically and horizontally, knife shafts carried by said supports, knives on said shafts, feed mechanisms coöperating respectively with the knives, and means located on opposite 120 sides of the knife shafts for adjusting the knife shafts and knives with respect to their respective feed mechanisms.
32. A machine of the class described having, in combination, a frame adapted to support two skiving knives in spaced relation, knife shafts having substantially the same inclination, feed mechanisms coöperating respectively with the knives, and means located on opposite sides of the knife shafts 125 130

- for adjusting the knife shafts and knives similarly with respect to their respective feed mechanisms. 37. The combination with a rotary disk knife, of a member comprising two legs extending into proximity to said knife, one of said legs comprising a hinged section which may be lifted when desired to permit a sharpening tool to be applied to said knife. 45
33. A machine of the class described having, in combination, skiving knives spaced apart in three directions, vertically, from side to side of the machine and from back to front of the machine, a feed mechanism for each knife, means for rotating said knives and feed mechanisms, and supporting means for the feed mechanisms constructed and arranged to permit said mechanisms to be swung away from the knives to facilitate grinding of the knives as well as removal 50 and replacement thereof. 38. A machine of the class described having, in combination, a skiving knife mounted on the frame of the machine, a supplementary frame pivoted to the main frame, and a feed roll and feed disk mounted on said supplementary frame. 55
- 10 39. A machine of the class described having, in combination, skiving mechanism, feed mechanism, a driving frame angularly and bodily movable with respect to the frame of the machine, driving means carried by the driving frame, and means for transmitting power from the driving means to the skiving and feed mechanisms. 60
- 15 40. A machine of the class described having, in combination, skiving mechanism, feed mechanism, a driving frame located in the rear of said mechanisms, driving means carried by the driving frame, belts connecting the driving means with the skiving 65 and feed mechanisms, and means for adjusting said driving frame bodily and angularly with respect to the frame of the machine. 70
- 20 41. A machine of the class described having, in combination, a skiving knife, means for feeding flexible material past said knife, a bracket by which said knife is carried, a slide-block to which said bracket is pivoted, means for moving the bracket about the pivot to vary the angle of the knife, a second slide-block upon which said first-mentioned slide-block is mounted, and means for adjusting said slide-blocks. 75
- 25 34. A machine of the class described having, in combination, two rotary skiving knives, feed rolls comprising a feed roll and a feed disk, rotary shafts upon which said rolls and disks are mounted, and bearings for said shafts, one of the bearings for the shaft of the disk of one feed mechanism being rigid with one of the bearings for the shaft of the roll of the other mechanism. 80
- 30 35. A machine of the class described, having, in combination, two skiving knives, feed rolls located to coöperate with said knives, means for rotating the knives, means for rotating one feed roll, means connecting the feed rolls to drive one from the other, and a support for the rolls movable toward and from the knives. 85
- 35 36. A machine of the class described having, in combination, two skiving knives, a feed roll and a coöperating feed disk for each knife, means for rotating the knives, means for rotating one of the feed rolls, means connecting the driven feed roll with the other feed roll and the feed disks to rotate said other roll and disks, and a support for the rolls movable toward and from the knives. 90

Copies of this patent may be obtained for five cents each, by addressing the "Commissioner of Patents, Washington, D. C."

NEWELL V. DYER.

It is hereby certified that in Letters Patent No. 1,308,776, granted July 8, 1919, upon the application of Newell V. Dyer, of Holbrook, Massachusetts, for an improvement in "Skiving-Machines," an error appears in the printed specification requiring correction as follows: Page 5, line 94, claim 3, after the word "arranged" insert the word *each*; and that the said Letters Patent should be read with this correction therein that the same may conform to the record of the case in the Patent Office.

Signed and sealed this 9th day of December, A. D., 1919.

[SEAL.]

M. H. COULSTON,

Acting Commissioner of Patents.

Cl. 69—16.
